(57) **CLAIM**

The ornamental design for a conical, four-blade, clockwise impeller, as shown and described.

DESCRIPTION

FIG. 1 is a front, top, right side perspective view of the conical, four-blade, clockwise impeller in accordance with the present design;

FIG. 2 is a front, top, left side perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a sectional view thereof, taken along the line shown in FIG. 2.

The broken lines in the disclosure of FIGS. 1-9 are understood to be for illustrative purposes of the environment and form no part of the claimed design.

1 Claim, 9 Drawing Sheets
